[57] **CLAIM**

The ornamental design for a cross-country ski vice, as
shown and described.

DESCRIPTION

FIG. 1 is a perspective view of cross-country ski vice
showing my new design;

FIG. 2 is a side elevation view thereof;

FIG. 3 is a top plan view thereof;

FIG. 4 is a front elevation view thereof; and,

FIG. 5 is a perspective view illustrating the manner in which
the cross-country ski vice is utilized in conjunction with other
equipment to fix a cross-country ski to a workbench to allow
maintenance work to be done on the ski surfaces etc.
